Des. 219,290
Patented Nov. 24, 1970

219,290

TOY ROCKET SHIP

Jack Rosenthal, South London, England, assignor to
Rovex Industries, Ltd., London, England, a corpora-
tion of Great Britain

Filed Dec. 29, 1969, Ser. No. 20,678

Term of patent 3½ years

Int. Cl. D21—02

U.S. Cl. D34—15

FIG. 4.

FIG. 2.

FIG. 1.

FIG. 3.

FIG. 5.

FIG. 1 is a side elevational view showing the design of
a toy rocket ship according to this invention;

FIG. 2 is a top plan view;

FIG. 3 is a bottom plan view;

FIG. 4 is a front elevational view; and

FIG. 5 is a rear elevational view.

I claim:

The ornamental design for a toy rocket ship, substan-
tially as shown.
